US0D1024078S

(12) **United States Design Patent** (10) Patent No.: **US D1,024,078 S**
(45) Date of Patent: ** Apr. 23, 2024

(54) **TABLET KEYBOARD COVER**

(71) Applicant: **WAYMEET (SHENZHEN)TECHNOLOGY CO., LTD.**, Shenzhen (CN)

(72) Inventors: **Zebo Ding**, Shenzhen (CN); **Yaohua Xie**, Shenzhen (CN); **Weiwei Xu**, Shenzhen (CN); **Xinlei Yu**, Shenzhen (CN)

(73) Assignee: **WAYMEET (SHENZHEN)TECHNOLOGY CO., LTD.**, Shenzhen (CN)

(**) Term: **15 Years**

(21) Appl. No.: **29/878,101**

(22) Filed: **Jun. 16, 2023**

(51) LOC (14) Cl. **14-02**

(52) U.S. Cl. USPC **D14/440**

(58) **Field of Classification Search**

USPC D14/440, 447, 455, 435, 439
CPC G06F 1/1628; G06F 1/1632; G06F 1/1671;
G06F 1/1626

See application file for complete search history.

Andrew C. Cheng

(57) **CLAIM**

The ornamental design for a tablet keyboard cover, as shown and described.

DESCRIPTION

FIG. 1 is a perspective view of a tablet keyboard cover showing my new design;

FIG. 2 is the second perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the tablet keyboard cover and form no part of the claimed design.

1 Claim, 8 Drawing Sheets
